(57) **CLAIM**

The ornamental design for a hammock stand as shown and described.

DESCRIPTION

FIG. 1 is a front, right perspective view of a hammock stand, showing my new design in a first configuration of use; FIG. 2 is a rear, left bottom perspective view thereof; FIG. 3 is a front view thereof; FIG. 4 is a rear view thereof; FIG. 5 is a left view thereof; FIG. 6 is a right view thereof; FIG. 7 is a top view thereof; FIG. 8 is a bottom view thereof; FIG. 9 is a front, right perspective view shown in a second configuration of use; FIG. 10 is a front, right perspective view shown in a third configuration of use; FIG. 11 is an enlarged view of detail 11 in FIG. 2; and, FIG. 12 is an enlarged view of detail 12 in FIG. 2. The broken lines shown in the drawings depict portions of the hammock stand that form no part of the claimed design.

1 Claim, 12 Drawing Sheets
